UNITED STATES PATENT OFFICE.

STALEY D. POOLE, OF MOLINE, ILLINOIS, ASSIGNOR TO THE DEERE & COMPANY, OF SAME PLACE.

TONGUELESS DISK WHEEL-PLOW.

SPECIFICATION forming part of Letters Patent No. 641,222, dated January 9, 1900.

Application filed September 10, 1898. Serial No. 690,672; (No model.)

To all whom it may concern:

Be it known that I, STALEY D. POOLE, a citizen of the United States, residing at Moline, in the county of Rock Island and State 5 of Illinois, have invented a new and useful Tongueless Disk Wheel-Plow, of which the following is a specification.

My present invention relates, primarily, to improvements in that kind or type of wheel 10 disk plows in which the plow-frame is supported on wheels, one of which wheels runs in advance of the furrow-cutting disk and in the previously-made furrow and another of which wheels runs in the furrow being made 15 and following said disk, both of which wheels are caster-wheels, while another wheel or wheels are also generally used and in which said caster-wheels are connected by a link in such manner that one of them in swinging 20 laterally or turning on its pivotal connection with the plow-frame will force the other wheel to swing therewith for the purpose of automatically guiding the plow. In wheel-plows of this type as made previous to my invention, as also in wheel-plows of the same type 25 in which ordinary moldboard-plows are used instead of disks, and in both of which the caster-wheels have been connected as above specified, said wheel-plows have in many instances been provided with tongues or guide-poles, which have been fixed at their rear 30 ends to the front caster-wheel or furrow-wheel in such manner that in operation the tongue or guide-pole as it would be swung laterally 35 independently of the plow-frame would thereby swing said front caster-wheel laterally, and the front caster-wheel would in turn swing the rear caster-wheel, and thereby guide the plow in making straight-away furrows, and 40 especially in turning the plow at the ends of bouts or furrows. The advantages of a tongueless plow are many and obvious in use. It is easier on the draft-animals; it allows them much greater freedom of action; it avoids all 45 rubbing or chafing of their sides; it avoids twisting on the neck-yoke, and often avoids upsetting the plow, caused by lengthening of the tongue and shortening of the traces relatively to other parts in turning, and thereby 50 cramping the wheels. In some instances the principal compensating advantage of a tongue

has heretofore been that it was the only known means of controlling and automatically casting the front furrow or caster wheel, which in turn castered and controlled the rear furrow-wheel. In tongueless wheel-plows as made in many instances previous to my invention a rear caster-wheel has in some cases been used; but in a number of cases where a front furrow-wheel has been used it has been 55 mounted on a spindle which was rigidly fixed to the plow-frame. Hence in turning the plow at the ends of furrows said front furrow-wheel must necessarily be dragged around sideways and the rear furrow caster-wheel 60 was free to roll around in the arc of a circle, and the two together failed to force the disk around in such manner as to compel it to cut out or plow the furrow in turning.

My invention has for its primary object to 70 entirely overcome these and other objectionable features of the types of wheel-plows referred to; and to this end and object my invention consists, substantially, in such features of construction, arrangement, and combination of parts as will hereinafter be more particularly described. When the tongue is dispensed with, a new mode of operation arises. The tongue is necessarily pivoted to swing laterally of the plow-frame, as it is 75 fixed to the pivoted vertical part of the front caster-wheel shaft. Hence in turning the plow at the ends of furrows the tongue is first 80 swung laterally by the draft-animals, and thereby acts on the front caster-wheel before 85 the plow-frame is moved. In fact, in all movements of the tongue laterally this is the case. Hence the mode of operation is different from that of the same devices without the tongue, in which case in turning the plow the 90 draft-animals, in beginning to turn, first act on the plow-frame, which then swings to deflect or swing the caster-wheels. This difference in the action on the caster-wheels effects a favorable result in turning the plow. The 95 mode of operation is, as is known, further different between said plows in that when the tongue is used the forward caster-wheel is the controlling-wheel and is first acted on by the tongue and then in turn swings the 100 rear caster-wheel, while without the tongue, the plow-frame being turned by the draft-

animals, swings away from the rear furrow or caster wheel, which is thus castered or swung and in turn acts on the front caster or furrow wheel and swings it. From the foregoing it will be seen that the two caster-wheels do not perform the same functions with the tongue as without it. With the tongue the forward caster-wheel controls the rear caster-wheel, while without the tongue the rear caster-wheel controls the forward caster-wheel, and the result in turning the plow is quite different, and the elements retained after the removal of the tongue do not perform the same offices or functions as before.

A further object of my invention is to provide means whereby the driver or operator may swing the forward caster-wheel alone or without a swinging movement of the rear 20 caster-wheel for the purpose of guiding the plow in making straight furrows; and to this end and object the invention consists in means interposed in the connecting-rod between the crank-arms of the front and rear 25 caster-wheels, by which means said connecting-rod may be used to swing the front caster-wheel independently of the rear caster-wheel. In connection with the last-named feature of my invention it further consists in means interposed in said connecting-rod by which the 30 length thereof may be adjusted for the purpose of adjusting and fixing the relative angles of the caster-wheels to each other and to the plow-frame.

A further object of my invention is to provide means by which the angle of the plane of rotation of the rear caster-wheel to the plow-frame may be adjusted for the purpose of running the disk or plow more or less landward; and to this end my invention consists 40 in an adjustable stop mechanism interposed between the bracket-arm which carries the rear caster-wheel and the plow-frame.

A further object of my invention is to provide an improved journal-bearing by which the disk plow is mounted on the link or standard which carries it.

The different novel combinations in which my improvements consist, the several and collective special and general operations of the component parts of said combinations, new and useful results which are the products of said combinations, and novel structural features and novel organizations of parts embodied in said combinations are hereinafter described and are respectively made the subject-matter of claims hereto appended.

In the accompanying drawings the different features of my improvements are shown 60 as embodied in the best way now known to me. Obviously, however, without departure from the purview of my invention these improvements may be used in wheel-plows differing in construction and organization of parts from the one shown by said drawings, in which—

Figure 1 is a top plan showing a tongueless-

disk three-wheel plow with my improvements incorporated therewith, as in operation plowing a furrow, the plow-beam shown as partly broken away; Fig. 2, a top plan, the beam partly broken away, showing the plow of Fig. 1 as in operation, turning at the end of a furrow; Fig. 3, a sectional elevation of the plow of Fig. 1 in the line 3 3 in Fig. 6 and side 75 elevation showing the plow-beam complete and the disk lowered, as in plowing; Fig. 3^a, a perspective of details hereinafter described, as seen from the rear and right-hand side of the plow; Fig. 4, a perspective of details hereinafter described, as seen from the rear and right-hand side of the plow; Fig. 5, same sectional elevation as Fig. 3 and side elevation, showing the disk in its elevated position; Fig. 6, a rear elevation showing the disk lowered, 80 as in plowing; Fig. 7, a perspective of details hereinafter described, as seen from the front and left-hand side of the plow; Fig. 8, a perspective of details seen from the same point of view as Fig. 4, and Fig. 9 a central vertical 90 section of the disk and adjacent parts.

Referring to the drawings, the numeral 4 designates the plow-beam, to the forward end of which is fixed the draft device 5.

Numerals 6 and 7 designate arms or brackets projecting laterally from opposite sides, respectively, of the plow-beam. The arm or bracket 6 has a crank-arm 8 journaled on its outer end, the crank end of which is a spindle on which the land-wheel 9 is journaled. 95 The usual locking hand-lever 10 adjusts the crank 8 in the ordinary manner for leveling the plow. The forward furrow-wheel 11 is journaled on the downwardly-inclined outer end or spindle of an arm or shaft 12, the vertical end 13 of which arm or shaft is journaled in a bearing 14 in the outer end of the bracket 7 and has one end of an inwardly-projecting crank-arm 15 fixed to its upper end. The rear end of the beam 4 is bent laterally and 100 turned upwardly to form a bracket 16, and a fixed standard 17 is bolted thereto. (See Fig. 8.) The U-shaped bar or link 18 spans the lower end of the fixed standard 17 and is pivotally connected therewith by a bolt 19. The 115 bar or link 18 extends forwardly and receives between its forward ends one end of a standard or link 20, which is bent, as shown best at Figs. 4 and 8, is pivotally connected at its lower end portion with the bar 18 by a bolt 120 21, and has the disk plow 22 mounted on its middle bent portion 23, as hereinafter described. The upper end 24 of the standard or link 20 is pivotally connected with the lower end of a bent hand-lever 25, which is pivoted 125 at its bend to a curved rack-bar 26, the lower end 27 of which rack-bar is bent at right angles to its vertical part and has slots 28, (see Figs. 1 and 2,) through which bolts 29 pass to adjustably fix it to the plow-beam, on which 130 it is seated. The hand-lever 25 has the usual spring-pawl 30 for locking it to the rack-bar 26.

By adjustments of the hand-lever 25, as indicated by dot-lines at Fig. 8, the depth of

plowing may be controlled, as the disk 22 is raised and lowered by the lever 25 raising or lowering the link or standard 20, on which said disk is mounted, and thereby swinging the distal end of the link 18 upwardly or downwardly, as the case may be. In thus adjusting the disk 22 in higher or lower positions, as described, the fixed standard 17, tilting standard or link 20, bar 18, and horizontal arm of the hand-lever 25 will raise and lower the disk, while its plane of rotation will remain substantially unchanged, as shown by dot-lines at Fig. 8. Assuming the disk 22 to be in its least inclined or in its nearest vertical position, as shown by full lines in the drawings, then by adjustments of the rack-bar 26 rearwardly on the plow-beam the hand-lever 25 will bodily, with its fulcrum, be moved rearwardly and in so moving will swing the upper end of the tilting link or standard 20 rearwardly, as shown by dot-lines at Fig. 3^a, and thus tilt the disk rearwardly at its upper side and increase the degree of its inclination on a plane parallel 25 with its axis of rotation or at right angles to its plane of rotation, as may be desired in different kinds of soil. After said adjustments of the rack-bar 26 it is fixed in place by the bolts 29. The driver's seat 31 is supported 30 on a bar 32, which is bolted to the part 27 of the rack-bar, so as to be adjustable therewith.

The rear furrow-wheel 33 is mounted in an ordinary manner on the outer bent and downwardly-inclined end 34 of a swinging bracket 35, the forward end part of which is bent upwardly to form a standard or spindle 36 at its forward end, which spindle is journaled in a head 37, fixed to the standard 17 and bracket 16. The spindle 36 projects above 40 the head 37 and has one end of a crank-arm 38 fixed thereto, the other end of said arm projecting outwardly therefrom with respect to the plow-beam when the rear caster-wheel is in its normal position, as in plowing straight furrows. A bracket 39 projects rearwardly 45 from the head 37, which carries it, and has a screw-threaded hole in its rear end part, through which an adjustable stop-bolt 40 is threaded and held in such position that one 50 side of the bracket 39 will contact therewith for alining the travel of the plow or machine, as hereinafter described. As in all plows of this type, the pressure against the disk of the soil of the furrow being turned would 55 swing the rear end of the plow-beam and parts mounted thereon landward, and a stop at one side of an arm 39 has heretofore been provided to prevent this. In different kinds of soil and when the disk is adjusted for different depths of plowing and at different angles the lateral pressure of the soil on the disk varies. By adjustments of the stop pin or bolt 40 to project to a greater or less extent through the bracket 39 the rear furrow-wheel 60 may be adjusted in an evident manner to hold it and to rotate at such different angles to the line of progression of the plow as

may be necessary to counteract different degrees of lateral pressure on the disk, and thereby cause the plow to advance in a proper line of progression when plowing at different depths and in soil of different conditions and with the disk more or less tilted.

A stud-bolt 42, (see Fig. 9,) fixed to the end 43 of the journal 44, on which the disk 22 is mounted, passes through the part 23 of the link or standard 20, and a nut 45 removably secures it in place on said part 23, with a lug 46 seated in a recess in the part 23 to prevent rotary movement of said journal. A cup-shaped cap 47, fixed to the disk by bolts 48, which pass through its annular flange 49 and through the disk, has an opening 50 through its cup-shaped part, through which opening the end 43 of the journal 44 passes, and one side or shoulder 51 of the enlargement 52 on said journal forms a bearing for the annular flange 53, the edge of which flange has a bearing on the part 43 of said journal. A further bearing is formed by a hub 54, which is seated 90 in a central hole in the disk 22 and has a socket 55, which receives the smaller and tapered part of said journal. The hub 54 has an annular outwardly-projecting flange 56 on its inner end, which is seated between 95 the disk and the cap 47, from which flange a lug 57 projects and seats in a corresponding recess 58 in the cup-shaped cap 47 for the purpose of locking said hub to said cap, whereby it will rotate positively with the 100 disk. An annulus-shaped bearing 59 encircles the journal 44 between the inner cup-shaped bearing 60 on the hub 54 and the confronting cup-shaped bearing 61 in the angle or shoulder between the tapering part of the 105 journal 44 and the enlargement 52 thereon. If preferred, ball-bearings may be used instead of the bearing 59. Oil or other lubricant is supplied through the inlet-hole 62 in the outer end of the hub 54, through which a 110 threaded bolt 63 is screwed to retain the oil, and preferably it may also project within the hub and its end form a bearing against the end of the journal 44. The end of the hub 54 may, however, abut against the outer 115 end of the journal 44 as a bearing therefor. By these means the disk is substantially mounted, while permitted to rotate freely, and in such manner that it may be readily, easily, and quickly removed for sharpening or for 120 other purposes by simply first removing the nut 45, and may be as quickly replaced, and while removed may be separated from the hub and other parts by removal of the bolts 48.

The distal ends or free ends of the crank-arms 15 and 38 are connected by a link 65, which link, in so far as its operations in turning the plow are concerned, may consist of a rod pivotally connected at its forward and rear ends, respectively, with the crank-arms 130 15 and 38. I have, however, shown this link adjustable, whereby it may be utilized in the new function of guiding the plow in straightening furrows by using it in adjusting the

plane of rotation of the forward furrow-wheel to the line of progression of the plow, a purpose for which it could not or cannot be used in a plow in which a tongue is connected with the forward furrow-wheel for guiding it. As shown best at Fig. 3, the link 65 is formed of a rod 66, pivotally connected at its forward end with the distal end of the crank-arm 15, a hand-lever 67, pivotally connected at its lower end with the distal end of the crank-arm 38 and pivotally connected a short distance from its lower end with the rod 66 a short distance from its rear end, and a curved rack-bar 68, fixed to the rod 66 in such position that an ordinary spring-dog 69, carried by the hand-lever 67, can be engaged with said rack-bar to lock all of said parts of the link 65 with respect to each other to form a positive connection between the crank-arms of the front and rear furrow-wheels or caster-wheels.

By swinging the hand-lever 67 rearwardly, as indicated by the dot-lines at Fig. 3, the crank-arm 15 will be swung rearwardly at its inner end, as shown best at Fig. 1, and will swing the spindle which carries the front caster-wheel 11 forwardly at its outer end, and thereby change the gather of said front caster-wheel by turning its forward side inwardly, and thereby increase its tendency to run to landward, and thus tend to carry the forward end of the plow or machine in that direction. By adjustments of the hand-lever 67 forwardly at its upper end it will be evident that the crank-arm 15 will be swung in an opposite direction, the front side of the caster-wheel 11 turned outwardly, and the machine be thereby guided in an opposite direction to that last described. In operating the hand-lever 67, as described, the crank-arm 38 will not be swung or deflected nor will the bracket-arm 35 be deflected. Hence the rear furrow-wheel 33 will not be swung or deflected thereby, and the link 65 may be said to be shortened by swinging the hand-lever 67 rearwardly and lengthened by swinging said lever forwardly. This shortening and lengthening arises from the different angles which the rod 66 and the hand-lever 67 assume to each other in the different adjustments of the hand-lever 67.

The hand-lever 67 is located in such close proximity to the driver's seat 31 that the driver can grasp its upper end and then by pressure on the ordinary thumb-latch 70 can release the dog 69 to permit of adjusting the hand-lever 67 and other parts, as hereinbefore described. By this means the hand-lever 67 can be used by the driver to cause the disk 22 to run more or less to landward, as may be necessary in straightening furrows which have become slightly crooked, as they are more or less likely to do with tongueless wheel-plows. By adjustments of said hand-lever the front caster-wheel may also be adjusted at different angles to the line of progression of the machine, and thereby cause the machine to run more or less to landward,

as may be found necessary in soils of different degrees of hardness and in different conditions when the disk is adjusted to plow at different depths and is adjusted at different degrees of inclination or for other purposes.

In plowing around "lands" or fields or other areas in which it is necessary to turn the plow substantially at a right angle to commence a furrow after completing a preceding furrow and with the disk adjusted by the hand-lever 25 in its least-inclined position, or substantially so, the machine is stopped with the disk 22 about the width of a furrow from the end of the furrow last made. The draft-animals are then started to turn around, and in so doing they will pull the forward end of the machine from its position shown at Fig. 1 around, as shown at Fig. 2, and as the machine is so swung its rear end will swing to the right, and thus caster on the rear furrow-wheel 33. The rear caster-wheel in thus changing its angular relation to the machine will by means of the crank-arms 15 and 38 and their connecting-link 65 swing the front caster-wheel 11 into the angular position with respect to the machine, all as shown at the same figure. It will be evident that when the two wheels 11 and 33 thus caster they will as the draft-animals are turned roll around each in the arc of a circle, and thus carry the machine around until it and the draft-animals are in proper positions to commence the next furrow, when the disk 22 will be found also in proper position for commencing said furrow. Then as the draft-animals are started forward the rear caster-wheel will at once swing into position, with its bracket 35 against the set-bolt 40, and in so swinging into position it will swing the front caster-wheel into proper working position. The disk is preferably adjusted in its least-inclined or nearest-vertical positions, as above described, for plowing in stubble, soft soil, or hard soil, even adobe, and set in this position the disk will throw the soil outwardly more. When most inclined, the soil will be thrown outwardly less and slide off the disk more easily and with the least disturbance of the soil.

When the disk 22 is adjusted in its most-inclined position, or substantially so, by swinging the hand-lever 25 to the rear, as is preferred by many farmers in plowing stiff sod—such as Johnson-grass sod, Bermuda-grass sod, or other stiff sod—it is preferable to continue the furrows to the sides of the field, then raise the disk above the ground, as shown at Fig. 5, and turn and drive across the headland, and then turn again to commence the return furrow. The caster-wheels 11 and 33 in turning in this manner will perform the same as hereinbefore described.

In some instances it may be preferable to turn the machine fully around to commence a furrow in an opposite direction from the furrow last made. In such case the disk is also elevated, and the draft-animals in turn-

ing will again carry the machine around, as above explained.

It will be evident that the machine will turn more easily with much less strain on its parts, 5 will hold its depth, and do better work when being turned when the forward and rear furrow-wheels caster than when they, or either of them, are rigid, and hence necessarily dragged sidewise in turning, as is the case with many 10 other tongueless plows. It will thus be seen that in turning the plow or machine toward the left hand under any circumstances and without any manipulation of the hand-lever 15 67 it will automatically be turned properly without any further aid than the natural side pull of the draft-animals after they have turned at an angle to the machine, and it will further be seen that the automatic action of 20 the caster-wheels is not dependent upon their connection with a tongue and that the rear caster-wheel entirely controls the action of the forward caster-wheel and that this invention thus has substantially a new mode of 25 operation, differing from many former tongueless wheel-plows.

The scraper 71 is of ordinary construction and is carried by the ordinary curved bar 72, which is adjustably connected with the standard 20.

30 I do not claim as my invention the means herein shown and described, consisting of the fixed standard 17, the pivoted link 18, the pivoted standard 20, and the short arm 25 of the hand-lever, which act collectively on the principle of a parallel ruler and by adjustments of said hand-lever at different inclinations are used to adjust the disk for plowing at different depths and also entirely above the surface of the ground without substantially changing the inclination of the disk in a plane parallel with its axis of rotation. 40 My invention in this connection consists in providing means whereby the standard 20 can be rocked or swung and adjusted in different 45 positions independently of the link 18 for the purpose of adjusting the disk at different inclinations in a plane parallel with its axis of rotation.

The standard 20 may be formed of a bent 50 bar, as shown, or otherwise constructed so as to have the proper bearing-surfaces at its ends for the lever 25 and the link 18 and an abutting surface for the disk-journal 44, Fig. 9, which will hold said journal and the disk 55 22 at the desired angle, and although I have specifically described the construction and relative arrangement of others of the several elements of my improvements, yet I do not desire to be confined to the same, as such 60 changes or modifications may be made as fairly fall within the scope of my invention.

Having thus described my invention, what I claim as new, and desire to secure by Letters Patent, is—

65 1. The combination, in a wheel-plow, of a plow beam or frame, a plow supported thereby, supporting-wheels, two of which are lo-

cated, one in advance of the plow, and the other in rear thereof, and both of which are caster-wheels, a movable link connection between said caster-wheels whereby upon the turning of the forward end of said beam or frame the control of said forward wheel is effected by the rearward wheel, and means under control of the operator interposed in 75 said link connection for swinging the front caster-wheel independently of the rear caster-wheel, substantially as described.

2. In a tongueless, disk, wheel-plow, and in combination, substantially as described, a 80 plow-frame, a plow mounted thereon, supporting-wheels, two of which are located, one in advance of the plow and the other in rear thereof, and both of which are caster-wheels, crank-arms projecting radially from the pivotal shafts on which said wheels caster, and a link connecting said crank-arms, and comprising a rod pivotally connected at one end with one of said crank-arms, a locking hand-lever pivotally connected at its end with the 85 other crank-arm and above its end with said rod, and a rack-bar mounted on said rod, whereby the dog on said hand-lever may engage therewith after adjustments to lengthen and shorten said link and thereby guide the 90 95 plow.

3. The combination in a wheel-plow, of a plow beam or frame, a front caster-wheel, a rear caster-wheel, means whereby upon the turning of the forward end of the beam or frame the control of the said forward wheel is effected by the rearward wheel, and means for effecting a swinging movement of said wheels under the control of the operator.

4. The combination in a wheel-plow, of a 105 plow beam or frame, a front caster-wheel, a rear caster-wheel, means whereby upon the turning of the forward end of the beam or frame the control of the said forward wheel is effected by the rearward wheel, and crank-arms and a hand-lever for effecting a swinging movement of said wheels under the control of the operator.

5. In a wheel-plow, and in combination, substantially as described, a plow frame, or beam, 115 supporting-wheels, a standard rigidly fixed to said plow frame or beam, a link pivotally connected at its rear end with said fixed standard, a standard pivotally connected at its lower end with the forward end of said link, 120 a plowing-disk mounted on said pivoted standard, a ratchet-bar adjustably mounted on said plow frame, or beam, and a bent, or elbow-shaped hand-lever pivotally connected at one end with said pivoted standard and 125 pivotally connected at its bend with said ratchet-bar whereby adjustments of said ratchet-bar will adjust said pivoted standard at different angles, and thereby adjust the inclination of said disk substantially as described.

6. In a disk wheel-plow, and in combination, substantially as described, a plow-beam 4, fixed standard 17, link 18, pivoted standard

- 20, disk 22, rack-bar 26 adjustably mounted on the beam 4, and bent hand-lever 25 pivotally connected at its bend with said rack-bar, and at its shorter end with the pivoted 5 standard 20, whereby adjustments of said rack-bar will adjust the pivoted standard 20 at different angles and thereby adjust the inclination of the disk 22 substantially as described.
- 10 7. In a tongueless wheel-plow, and in combination, substantially as described, a plow-frame, a plow mounted thereon, supporting-wheels, one of which is a caster-wheel located to run in the furrow in rear of the plow, and 15 a set-bolt, or stop, adjustably seated in said plow-frame to contact with the arm on which the caster-wheel is journaled.
8. In a tongueless wheel-plow, and in combination, substantially as described, a plow- 20 frame, a plow mounted thereon, supporting-wheels, two of which are located, one in advance of the plow and the other in rear there-

of, and both of which are caster-wheels, crank-arms projecting radially from the pivoted shafts on which said wheels cast, a link 25 pivotally connected with said crank-arms, and a set-bolt, or stop, adjustably seated in said frame to contact with the arm on which the caster-wheel is journaled.

9. In a disk-wheel-plow, a combination comprising a furrow-forming disk 22, a standard 20, a journal 44 having a stud-bolt 42 with enlargements 43 and 52 and a lug 46 on one of its ends, a hub 54, a bearing 59, a cap 47, bolts 48, oil-inlet 62, bolt 63, and nut 45, all 35 constructed and combined substantially as described and for the purpose specified.

In testimony whereof I affix my signature in presence of two witnesses.

STALEY D. POOLE.
